DESIGN FOR A CLAMP FOR USE IN VULCANIZING

Paul Van Cleef, Chicago, Ill., assignor to Van Cleef Bros., Chicago, Ill., a partnership composed of Noah Van Cleef, Felix Van Cleef and Paul Van Cleef

Application April 9, 1938, Serial No. 76,412

Term of patent 7 years

To all whom it may concern:

Be it known that I, Paul Van Cleef, a citizen of the United States, residing at Chicago, in the county of Cook and State of Illinois, have invented a new, original, and ornamental Design for a Clamp for Use in Vulcanizing, of which the following is a specification, reference being had to the accompanying drawing forming a part thereof.

Figure 1 of the drawing is a perspective view of a clamp for use in vulcanizing, showing my new design; and

Figure 2 is a side view of the clamp.

I claim:

The ornamental design for a clamp for use in vulcanizing substantially as shown.

PAUL VAN CLEEF.
